Application December 14, 1954, Serial No. 475,223

Claims priority, application Germany December 30, 1953

11 Claims. (Cl. 28—1)

This invention relates to the manufacture of lined fabrics, and more particularly to the manufacture of woven, lined tubular fabrics.

An object of the invention is to provide a method by means of which seamless woven, lined tubular fabrics may be manufactured.

Another object of the invention is to provide a device by means of which lined tubular fabrics may be manufactured on a circular loom.

Other objects and structural details of the invention will be apparent from the following description when read in conjunction with the accompanying drawings forming part of this specification, wherein the device for use on a circular loom according to the invention is illustrated by way of example.

Fig. 1 is a fragmentary vertical sectional view of the device according to the invention, some parts being broken away for the sake of better illustration.

Fig. 2 is a sectional view taken on line II—II of Fig. 1, illustrating means broken away in Fig. 1.

Fig. 3 is a sectional view taken on line III—III of Fig. 1, illustrating the pressing means of the device, partly broken away in Fig. 1, and

Fig. 4 is a side elevation, partly in section, of the pressing means shown in Fig. 3.

Fig. 5 shows at 53 the storing in rolls of two sheets (54 and 55) of material previously coated with an adhesive product, these two sheets being rolled up with the two adhesive faces one against the other.

Fig. 6 shows a heating device placed in the weaving zone itself. This device substantially comprises a heating ring 50 separated by a thin conducting wall 51 from the fabric-and-sheet product coated with the thermoplastic which is to insure adhesion. The heating of the ring may be effected by a wound electric resistance or by a circulating hot fluid, liquid, steam or air. The heat is limited to the desired zone by the protection of a thermal insulator 40 placed outside of the heating ring.

Fig. 7 illustrates a modification of the heating system. The undried adhesive product which may have been applied through coating by means of a roller and vat or which may have been pulverized or deposited at 40' (Fig. 6) is caused to form a bond by means of pressure in the rolls and is then dried at 44 below the weaving zone by a lamp or bank of lamps.

Referring now to Fig. 1, 36 generally indicates the auxiliary device according to the invention attached to a circular loom with a horizontal shed 37 and a weaving ring 33. The tubular fabric 38 woven on the circular loom is drawn off downwardly by a suitable drawing-off mechanism generally indicated by 35. The drawing-off mechanism is driven in a suitable manner by the main shaft of the loom.

Two supply rollers 1, each having a sheet 3 of lining material, of paper for example, wound thereon are rotatably mounted diametrically opposite to each other, on a frame 2 adjustably mounted on a fixed vertical shaft 9 coaxially arranged with the longitudinal axis of the cir-

2

cular loom. One surface of the sheet 3 of paper is coated with an adhesive, for example an asphaltic cement. After passing the adjustable guide mechanism 5 the coated surface of the paper 3 faces outward, so that, behind point 4 (Fig. 1) in the weaving zone and within the weaving ring 33 of the loom, it may be cemented to the inner surface of the tubular fabric 38 woven in said weaving zone. The width of each of these sheets 3 of paper is such as to equal one half of the development of the woven tubular fabric plus the width of an overlap 3' of several centimeters (Fig. 3).

Upon the cementing of the paper panel 3 to the tubular fabric 38 within the weaving ring 33 the paper 3 firmly adheres to the inner surface of the fabric 38. As the drawing-off mechanism 35 draws off the collapsed tubular fabric 38 with the paper lining 3 cemented to the inner surface thereof, the feeding speed of the paper 3 equals the drawing-off speed of the fabric 38. The tension in the paper 3 may be adjusted by a suitable adjustment 20 of the guiding mechanism 5 by means of the lever 5'.

In order to assist the paper 3, after its unwinding from the supply roll 1 and passing guide mechanism 5, in changing from its plane shape into the required semi-cylindrical shape, another guiding device is provided which is mounted on arms 40, 41 rigid with a sleeve 25 adjustably attached to the shaft 9 by a screw 42. Said guiding device comprises small rollers 28 journaled at the ends of bars 26, 27 secured to the arms 40 and 41 respectively. Said rollers 28 urge the paper 3 inwardly into curved shape.

Above the weaving zone, i.e. above the upper edges of the weaving ring 33 several heating lamps 6 radiating infra-red rays are mounted on a ring 29 carried by rods 30 hinged to the frame 2 at 31. The intensity of radiation of these lamps acting on the coated surface of the paper 3 within a range limited by the circles 7 and 4 (see Fig. 1) is adjusted in accordance with the speed of operation and, thus, output of the loom in such a manner that the asphaltic cement on the paper 3 is soft enough to stick to the fabric 38 when it contacts the latter beyond circle 4. The switching-on and switching-off of these lamps is synchronized with the operation of the loom. In order to avoid faults in the cementing of the paper 3 to the fabric, means may be provided by which the lamps 6 may be switched on before the loom is started after a relatively long standstill.

In order to paste the paper 3 firmly to the fabric 38 upon entering the weaving zone it is pressed against the fabric 38 by means of a pressing device 45 arranged within the weaving ring 33. As best shown in Fig. 3, said pressing device 45 comprising four wooden rollers 8 may rotate around the vertical axis of the loom, coinciding with the longitudinal axis of the shaft 9, in the direction of the arrow A, i.e. opposite to the direction of rotation 50 of the shuttles. The speed of rotation of said pressure device 45 must be such that the path described by the rollers 8 on the downwardly moving fabric 38 is in the form of a helix which is so flat that during each revolution of the pressure device 45 the pressure zone of each 55 wooden roller 8 overlaps a portion of the pressure zone of the preceding roller.

As best shown in Figs. 3 and 4, a bracket 10 is secured to the upper part of a sleeve 11 fixed to the shaft 9. A hub 12 provided with four hollow spokes 13 is rotatably mounted on the lower part of sleeve 11. A sleeve 22 is axially movable in each of the hollow spokes 13. Each wooden roller 8 is rotatably arranged in the forked outer end of such a sleeve 22. One end of a coil spring 20 arranged within each sleeve 22 presses against an inner wall 46 of the associated sleeve 22; the other end of said spring 20 presses against the bottom 21 of the hollow

spoke 13. A rod 23 on the lower part of sleeve 22 carrying the rollers 8 is guided in a hole of a projection 24 of the hollow spoke 13 in order to prevent the parts 22, 23 bearing the rollers 8 from rotation. On the bracket 10 an electromotor 15 is mounted which by means of gear wheels 16, 17 and a worm 18 rotates a worm wheel 19 secured to the hub 12 being rotatable on the sleeve 11 and carrying the described pressure device. This pressure device can be used for various width of a fabric or diameter of a tubular fabric respectively by a simple adjustment of the members carrying the rollers 8.

The described and illustrated device according to the invention is relatively simple and inexpensive. It may be readily mounted on and dismounted from a loom. By the use of the device the doubling of the fabric, i.e. the attachment of a lining to the fabric in a separate working step is avoided. Furthermore, the device according to the present invention renders possible the manufacture of seamless woven tubular fabrics with a lining attached thereto. The lining may be of any suitable material, for example paper, rubber, a plastic, or any other synthetic or natural material. Any suitable adhesive may be used for cementing the lining to the fabric.

A seamless woven, lined tubular fabric according to the invention is especially useful for the manufacture of bags, sacks or the like, wherein the lining is used to prevent the escape of material placed into the bag or the like through pores of the fabric thereof and to prevent further outside air or moisture from entering into the bag or the like.

Hitherto lined fabrics are made in such a way that the fabric is woven on an ordinary loom and subsequently a lining is applied to the flat fabric in a separate step on a pasting machine requiring additional space in the factory and operators for servicing same, whereby the costs of manufacture become very high. The bags and sacks produced from doubled fabrics woven on ordinary looms and lined in this hitherto customary manner, however, have at least one lateral seam. As a matter of fact, the protective lining and, of course, the fabric are interrupted at such a seam, so that moisture is liable to enter, or powdery material may escape through the seam.

These drawbacks are avoided by the present invention, according to which a tubular fabric is woven on a circular loom and panels of a lining material, preferably a non-textile material, are cemented to the inside of said tubular fabric in the same operation.

The woven tubular fabric manufactured in the manner described above comprises two panels of non-textile material cemented to the inner surface of the tubular fabric. If desired, however, more than two such panels could be cemented to the tubular fabric in a similar manner.

Instead of using two individual supply rolls with a winding of a sheet of lining material on each roll, only one supply roll could be arranged above the loom, the sheet wound thereon consists of two non-textile layers sticking to each other through an adhesive. In such a case, however, means must be provided by which the sheet consisting of two layers at first is guided upwardly, whereupon the two layers are separated from each other by rollers and guided laterally and downwardly to the weaving zone, where, as in the illustrated example, a pressure device is arranged to press both layers onto the inner surface of the tubular fabric, it being understood that the coated surface of each layer faces the inner surface of the tubular fabric.

Instead of using supply rolls with a winding of a sheet coated at one of its surfaces with an adhesive, it is possible to use rolls with a winding of a sheet free from any adhesive coating and to apply an adhesive substance to the sheet, by spraying or spreading-on the adhesive, for example, during its downward movement to the weaving zone. In this case, of course, the adhesive must be subjected to a heat treatment simultaneous with or short-

ly after the pressing-on of the sheet to the tubular fabric so as to cause a drying and binding of the adhesive. Preferably an adhesive is used, which binds fast enough so that the normal speed of operation of the loom may be maintained.

When an asphaltic cement is to be applied to the sheet, preferably heating devices with automatic temperature control are used.

The heating device causes a heating of the adhesive or 10 the coated sheet or the thermoplastic sheet (if such a material is used) to the desired temperature necessary to cause the adhesive effect.

If desired the weaving ring arranged in the weaving zone can be designed as a heating means which may be 15 switched on and off together with the motor driving the loom.

Instead of a dynamic pressure device as that shown in the drawings (see Figs. 3 and 4), which is automatically started and stopped with the starting and 20 stopping of the loom, stationary pressure means may be provided within the weaving ring, such as leaf springs or spring-loaded pressure members.

We have described preferred embodiments of our invention, but it is understood that this disclosure is for 25 the purpose of illustration and that various omissions or changes in shape, proportion and arrangements of parts, as well as the substitution of equivalent elements for those, herein shown and described may be made without departing from the spirit and scope of the invention as 30 set forth in the appended claims.

What we claim is:

1. A method for the manufacture of a woven, lined tubular fabric, comprising the steps of: weaving a tubular fabric on a circular loom having a weaving ring, supplying 35 to the interior of said weaving ring a lining material coated at one of its surfaces with a material capable of becoming an adhesive, processing said material so that it becomes an adhesive, and bringing the adhesive opposite the inner surface of the tubular fabric, drawing off the tubular fabric and the lining material at the same speed, and pressing the adhesive against the inner surface of said tubular fabric for cementing the former to the latter.

2. In a method as claimed in claim 1, the step of 45 subjecting the coated surface of the lining material to a heat treatment.

3. In a method as claimed in claim 2, the step of subjecting the coated surface of the lining material to a heat treatment before it reaches the weaving ring.

4. In a method as claimed in claim 2, the step of 50 subjecting the coated surface of the lining material to a heat treatment during its passage through the weaving ring.

5. In a circular loom, the combination of: a weaving 55 ring, means for supplying at least one length of lining material coated at one of its surfaces with an adhesive into the interior of said weaving ring, guiding means for guiding the supplied lining material to said weaving ring with its coated surface facing the inner surface of the tubular fabric woven by the implements of the loom, heating means for heating the coated surface of the lining material, pressing means for pressing said lining material onto the inner surface of the tubular fabric so as to cause an adhesion of the lining material to the fabric, means for drawing off the tubular fabric with the lining material cemented thereon, said heating means comprising a heated device arranged above said weaving ring for heating the coated surface of the lining material in the zone above the weaving ring.

6. In a circular loom, the combination of: a weaving 60 ring, means for supplying at least one length of lining material coated at one of its surfaces with an adhesive into the interior of said weaving ring, guiding means for guiding the supplied lining material to said weaving ring with its coated surface facing the inner surface of

the tubular fabric woven by the implements of the loom, heating means for heating the coated surface of the lining material, pressing means for pressing said lining material onto the inner surface of the tubular fabric so as to cause an adhesion of the lining material to the fabric, means for drawing off the tubular fabric with the lining material cemented thereon, said heating means comprising a ring arranged above said weaving ring, and a series of infra-red lamps mounted on said ring for emanating rays onto the coated surface of the lining material in a zone above the upper edge of said weaving ring.

7. In a circular loom, the combination of: a weaving ring, means for supplying at least one length of lining material coated at one of its surfaces with an adhesive into the interior of said weaving ring, guiding means for guiding the supplied lining material to said weaving ring with its coated surface facing the inner surface of the tubular fabric woven by the implements of the loom, heating means for heating the coated surface of the lining material, pressing means for pressing said lining material onto the inner surface of the tubular fabric so as to cause an adhesion of the lining material to the fabric, means for drawing off the tubular fabric with the lining material cemented thereon, said heating means comprising a heating device arranged in said weaving ring for heating the coated surface of the lining material during its passage through said weaving ring.

8. In a circular loom, the combination of: a weaving ring, means for supplying at least one length of lining material with a coating into the interior of said weaving ring, means for processing said coating so that it becomes an adhesive, the adhesive facing the inner surface of the tubular fabric woven by the implements of the loom, pressing means arranged within said weaving ring for pressing the lining material with the surface bearing the adhesive against the inner surface of said tubular fabric, and means for drawing-off the tubular fabric together with the lining material.

9. In a circular loom as claimed in claim 8, said pressing means being arranged within said weaving ring, and a heating device arranged at the level of said pressing means for heating the adhesive in the pressing zone.

10. In a circular loom as claimed in claim 8, said pressing means being arranged within said weaving ring, and a heating device arranged below the level of said pressing means for heating the adhesive after passing the pressing zone.
11. In a circular loom, the combination of a weaving ring, means for supplying at least one length of lining material coated at one of its surfaces with an adhesive into the interior of said weaving ring, guiding means for guiding the supplied lining material to said weaving ring with its coated surface facing the inner surface of the tubular fabric woven by the implements of the loom, heating means for heating the coated surface of the lining material, pressing means for pressing said lining material onto the inner surface of the tubular fabric so as to cause an adhesion of the lining material to the fabric, means for drawing off the tubular fabric with the lining material cemented thereon, said supplying means comprising a roller having a winding of a sheet of lining material consisting of two layers sticking to each other through an adhesive, means for separating said two layers from each other at a point between said supplying means and said weaving ring, and guiding means for guiding the separated layers to said weaving ring in a position wherein the surfaces carrying the adhesive face the inner side of the tubular fabric.
